[57]

CLAIM

The ornamental design for a fishing lure, as shown and described.

DESCRIPTION

FIG. 1 is a perspective view of an embodiment of my design showing the lure with a diving bill on the front, and the tail curved upwardly;

FIG. 2 is a perspective view of another embodiment of my design similar to the embodiment of FIG. 1 but with the tail curved downwardly;

FIG. 3 is a perspective view of still another embodiment of my design similar to the embodiment of FIG. 1 but with a modified bill on the front portion;

FIG. 4 is a perspective view of yet another embodiment of my design similar to the embodiment of FIG. 2 but with a modified bill on the front portion.
